BUSHING SEALING CAP

Gordon A. Burr, Wilkinsburg, and Edwin E. Arnold, Pittsburgh, Pa., assignors to Westinghouse Electric & Manufacturing Company, East Pittsburgh, Pa., a corporation of Pennsylvania

Application March 29, 1934, Serial No. 717,980

3 Claims. (Cl. 173—318)

Our invention relates to insulating bushings commonly used to protect the leads of encased high-tension electrical apparatus, such as transformers and circuit breakers, and, more particularly, to an improved bushing construction whereby relative movement of the bushing parts under the influence of temperature variations is permitted without injury to the bushing elements, and without affecting the insulating characteristics of the bushing as a whole.

Bushings of the type now generally used comprise a substantially cylindrical weather casing adapted to be mounted on the tank of a transformer, for example, and a conductor extends axially of the casing into the tank for connection with the transformer winding. The free end of the conductor extends beyond the upper end of the casing for connection with the circuit with which the transformer is to be associated. The conductor and casing are secured together at both ends of the casing to form a fluid-tight chamber for an insulating fluid which surrounds the conductor and substantially fills the casing.

Such bushings are generally exposed to varying weather conditions with temperature ranging from below zero to over 100° F., and in view of the dissimilarity in coefficients of thermal expansion of the conductor and casing, as well as volumetric changes in the insulating fluid, considerable difficulty has been experienced in maintaining a fluid-tight joint between the ends of the casing and the conductor.

It is an object of our invention, therefore, to provide a bushing construction which shall be fluid-tight over a wide range of temperature values.

It is a further object of our invention to provide, in a bushing construction of the fluid-filled type, a seal between the conductor and the open end of the weather-casing which will permit relative axial expansion of these elements and, at the same time, serve as a reservoir for the insulating fluid.

In practicing our invention, we provide a seal comprising an expandable chamber surrounding the conductor and resting upon the upper end of the weather casing, and means cooperating with the conductor engaging the upper exterior face of the chamber for compressing the latter to maintain it in operative position.

Referring more specifically to the drawing, Figure 1 is a view in elevation of a complete bushing unit constructed in accordance with the present invention.

Fig. 2 is a view in vertical section of a portion of the structure shown in Fig. 1.

Referring to Fig. 1, the bushing assembly comprises an elongated conductor 2 which may, as in the present embodiment, be wrapped with a plurality of alternate layers of conducting and

insulating material to constitute a bushing of the condenser type. The upper half of the conductor is enclosed in a weather-casing of porcelain or other suitable dielectric material and is provided with creepage flanges 3 in accordance with usual practice.

A metallic mounting flange 6 surrounds the wrapped conductor in fluid-tight relation and constitutes a support for the weather casing, a suitable gasket 7 being interposed between abutting faces of the casing and flange to provide a fluid-tight joint.

In practice, the lower half of the conductor is inserted through an opening in the tank of a transformer or circuit-breaker and the bushing assembly is maintained in position by suitable means securing the laterally extending flange 8 to the tank around the opening therein. This type of construction is common practice and need not be described in detail.

The bushing is adapted to be filled with an insulating fluid which may be more or less viscous, such as asphaltum or oil.

Referring more particularly to Fig. 2, the conductor 2 extends above the upper edge of the casing 4 and the two are secured in operative relation by means of a chambered casting 10 which is substantially of bowl-shape and is provided with a central aperture to permit the end of the conductor to extend therethrough.

The external contour of the casting is rounded to reduce the concentration of the electrostatic field at this end of the bushing, which is to be connected to the high-tension line, to obtain an improved stress distribution between the top of the casting and the grounded flange 6.

The casting 10, in the present embodiment, is an aluminum alloy which is sufficiently dense to prevent the leakage of the insulating fluid through its walls, and its side walls are relatively thin to permit a limited expansion and contraction of the casting axially of the conductor.

Within the casting 10, and depending from the top thereof, three legs 11 are provided which cooperate with a seat 12 on the bottom of the casting. In practice the legs and seat may be cast integral and subsequently separated by a machining operation. Although this particular procedure is not essential, it is an efficient way to obtain an accurate spacing between the ends of the legs 11 and seat 12.

The lower face of the casting is provided with a peripheral seat adapted to rest upon the upper edge of the weather casing 4, and a gasket 13 is interposed between the engaging faces to provide a cushioned fluid-tight joint. The inner peripheral edge of the bottom wall of the casting is provided with a depending flange 14 which extends into the casing 4, as shown.

The upper wall of the casting is provided with

an interiorly-threaded axially extended flange 15 and means defining a recess surrounding the conductor 2. Packing, such as asbestos rope 16 impregnated with a suitable viscous compound 5 which will not harden with age, is disposed in said recess, and is compressed in position to provide a fluid-tight seal by means of a packing-nut 17 which cooperates with the interior threads of the flange 15. After the packing nut has been seated it is sealed in position by a quantity of sealing material 18 of the molded type, such as "Bakelite."

The casting 10 is maintained in position by means of a cap 20 which is provided with a 15 threaded opening for cooperation with the threaded end of the conductor 2, and has a depending flange 21 adapted to surround the flange 15 on the casting to provide a weather-shed. The lower face of the cap 20 is adapted to engage the upper edge of the flange 15 and, if desired, a gasket 22 may be inserted therebetween to provide a resilient fluid-tight seal therebetween. Ears 23 on the cap 20 may be provided to facilitate handling of the bushing during its 25 installation or subsequent removal. The upper end of the threaded opening in the cap may be chamfered, as shown, to receive a ring of solder 24.

In assembling the structure described, the casting 4 is filled with an insulating fluid 25 and some of the fluid is disposed in the casting 10 before it is placed in position on the casing 4 with the gasket 13 between the engaging surfaces. The volume of insulating fluid is so chosen that its 35 minimum height, under various temperature conditions, will be level with or slightly above the upper edge of the casing 4, so that the fluid is maintained in contact with the gasket 13 to further insure that air and moisture may not be 40 drawn into the casing at this point.

The packing 16 is then placed in position and compressed by means of the packing-nut 17 to obtain a fluid-tight joint between the top of the casting and the conductor 2.

45 The casting is then compressed within its elastic limit, so that the legs 11 abut the seat 12 and cap 20 is screwed down upon the gasket 22 and flange 15 to maintain the casting in its compressed condition, and to compress the gasket 13 to maintain a positive fluid-tight joint between the bottom of the casting 10 and the casing 4. The amount the casting 10 may be compressed is limited by the three legs 11, but is sufficient to insure that subsequent expansion of the casting 55 may occur under the varying temperature conditions encountered in practice, without disrupting the seal at the gasket 13.

It should be apparent from the foregoing that under conditions of relative movement between 60 the conductor 2 and casing 4, the expandable casting 10 will follow such movements and maintain a fluid-tight seal between the conductor and casing. Although it is true that such relative movement will be small, it has been found, in prior 65 constructions, to be sufficient to break the seal between the conductor and casing, permitting the insulating fluid to escape or permitting air and moisture to be drawn into the casing. These difficulties have been eliminated in the construction of our invention.

70 In order to permit testing of the fluid-tight

character of the bushing, after assembly, a plug 26 may be provided in the upper face of the casting so that the interior of the bushing may be subjected to a fluid pressure or vacuum, as desired.

Various modifications may be made in our invention without departing from the spirit and scope thereof, and we desire that the invention shall be limited only by the scope of the appended claims.

We claim as our invention:

1. In a bushing for high-tension electrical apparatus including an elongated cylindrical casing of insulating material, a conductor extending therethrough with its free end projecting beyond the end of said casing, and a quantity of insulating fluid substantially filling said casing, means constituting a combined fluid reservoir and expansion chamber for securing the free end of said conductor to the end of said casing in fluid-tight relation and premitting relative axial expansion of said conductor and casing, comprising a chambered casting having a rounded exterior surface and being expansible axially of the conductor, one face of said chamber being proportioned to engage the upper edge of said casing, means cooperating with said conductor engaging the other face of said chamber for compressing and deforming said chamber to maintain it in operative position, and means for limiting the compressive movement of said chamber.

2. In a bushing for high-tension electrical apparatus comprising a cylindrical casing of insulating material having a conducting rod extending axially therethrough, one end of said casing being rigidly mounted with respect to said conductor and the free end of said casing terminating adjacent to the free end of said conductor, an axially expansible member of bowl-shape having an axial aperture to permit the conductor to extend therethrough and having a lower face proportioned to rest upon the end face of said casing, means on the upper part of said member for embracing said conductor in fluid-tight relation, and means engaging said conductor for compressing said member a sufficient amount to maintain it in operative position throughout the range of relative axial expansion and contraction of the conductor and casing.

3. In a bushing comprising a cylindrical casing 5 of insulating material having a conducting rod extending axially therethrough, one end of said casing being rigidly mounted with respect to said conductor and the free end of said casing terminating adjacent to the free end of said conductor, an axially expansible member of bowl-shape having an axial aperture to permit the conductor to extend therethrough and having a lower face proportioned to rest upon the end face of said casing, means on the upper part of said member for embracing said conductor in fluid-tight relation, means cooperating with said conductor for exerting a compressive force on said member to maintain it in operative position, a quantity of insulating fluid filling said casing and partially filling said expansible member, and means within said member for limiting the compressive movement thereof.
